[57] CLAIM

The ornamental design for a skid shoe, as shown and described.

DESCRIPTION

FIG. 1 is a top plan view of the skid shoe of my new design; FIG. 2 is a front elevational view thereof;

FIG. 3 is a rear elevational view thereof;

FIG. 4 is a bottom plan view thereof;

FIG. 5 is a side elevational view thereof, the opposite side being a mirror image thereof;

FIG. 6 is an enlarged sectional view taken along the line 6—6 of FIG. 1;

FIG. 7 is a top plan view of a second embodiment of FIG. 1;

FIG. 8 is a front elevational view of FIG. 7;

FIG. 9 is a rear elevational view of FIG. 7;

FIG. 10 is a bottom plan view of FIG. 7;

FIG. 11 is a side elevational view of FIG. 7, the opposite side being a mirror image thereof; and,

FIG. 12 is an enlarged sectional view taken along the line 12—12.
